(57) **CLAIM**

The ornamental design for a junction box for solar panel as shown and described.

DESCRIPTION

1.1 : Right

1.2 : Top

1.3 : Bottom

1.4 : Left

1.5 : Perspective

1.6 : Front

1.7 : Perspective

1.8 : Perspective

1.9 : Back

The design consists of junction box for solar panel; The parts shown by means of broken lines in the reproductions are not part of the claimed design.
